UNITED STATES PATENT OFFICE.

CARL M. TIPOGRAPH, OF NEW YORK, N. Y.

SWEATBAND.

1,392,539.

Specification of Letters Patent.

Patented Oct. 4, 1921.

Application filed April 29, 1921. Serial No. 465,524.

To all whom it may concern:

Be it known that I, CARL M. TIPOGRAPH, a citizen of the United States, residing at New York, in the county of New York and State 5 of New York, have invented certain new and useful Improvements in Sweatbands, of which the following is a specification.

My invention relates to a new and improved form of sweat band. As sweat 10 bands have been heretofore made, it has been very difficult to perform the necessary sewing operations upon them, and the sewing operation caused the sweat band to lose the shape which had been originally im- 15 parted thereto.

One of the objects of my invention is to provide a sweat band which can be made with a minimum of labor. Another object of my invention is to provide a sweat 20 band which can be easily sewed without injuring either the sweat band or the sewing machine. Other objects of my invention will be shown in the following description and drawings which illustrate a 25 preferred embodiment thereof.

Figure 1 is a view of the blank from which the sweat band is made.

Fig. 2 is a section along the line 2—2 of Fig. 1.

Fig. 3 is an elevation of the completed sweat band.

Fig. 4 is a section along the line 4—4 of Fig. 3.

The sweat band which is made of leather 35 or other suitable material has a body portion 1 and a flap portion 2 which is adapted to be bent over along the arcuate line 5, as illustrated in Fig. 3.

The arcuate line 5 may be imaginary.

It will be noted that the body portion 1 is pointed and has two arcuate sides 5 and 6, the curvature of the side 5 being much larger than the curvature of the side 6.

When the flap portion 2 is bent over, the 45 ends 7 thereof are substantially perpendicular to the tangents at the adjacent portions of the arcuate side 5, and as can be clearly seen from Fig. 3, the ends 7 are inclined toward each other. The flap portion 2 can 50 be secured in position by any suitable adhesive.

Since the completed sweat band has pointed ends and since the ends 7 of the flap portion are removed at some distance from the said pointed ends, the sweat band can be 55 readily run through a sewing machine so as to provide a line of stitching adjacent the side 6 without in any way disturbing the flap portion 2. If the sweat band were made of a double thickness at the ends 60 thereof as has heretofore been customary, then the sewing was very difficult and the action of the sewing machine injured the flap and loosened it from the body portion 1. By suitably shaping the sweat band as 65 before indicated, before pasting the flap 2 to the body portion 1, superior results are secured.

I have described a preferred embodiment of my invention, but it is clear that numerous changes and omissions can be made without departing from its spirit.

I claim:

1. A sweat band having a body portion provided with substantially pointed ends 75 and having a flap portion with its ends spaced from said pointed ends.

2. A sweat band having a body portion provided with substantially arcuate sides and having a flap portion bent over upon 80 and secured to the said body portion, the ends of said flap portion being spaced from the ends of the said body portion.

3. A sweat band having a body portion provided with arcuate sides terminating in 85 pointed ends, one of said arcuate sides being of smaller curvature than the other, the said body portion having a flap portion connected thereto adjacent the said side of smaller curvature, the said flap portion being doubled over on the said side of smaller curvature, and being secured to the said body portion, the ends of said flap portion being inclined to each other, and being substantially perpendicular to the adjacent tangents of said side of smaller curvature, the ends of the said flap portion being spaced from the pointed ends of the said body portion. 95

In testimony whereof I hereunto affix my 100 signature.

CARL M. TIPOGRAPH.
